CLAIM

The ornamental design for a light housing for a power tool, as shown and described.

DESCRIPTION

FIG. 1 is a perspective view from the right side showing our new design for a light housing.

FIG. 2 is a front elevational view of the light housing.

FIG. 3 is a left side elevational view of the light housing.

FIG. 4 is a right side elevational view of the light housing.

FIG. 5 is a top plan view of the light housing; and,

FIG. 6 is a bottom plan view of the light housing.

The broken line showing is for illustrative purposes only and forms no part of the claimed design.
